ELECTRON DISCHARGE SIGNAL-SAMPLING DEVICE

Charles J. Hirsch, Douglaston, N. Y., assignor to Hazeltine Research, Inc., Chicago, Ill., a corporation of Illinois

Application April 9, 1952, Serial No. 281,353

14 Claims. (Cl. 250—27)

1

General

This invention relates to electron-discharge signal-sampling devices and, more particularly, to such devices of the type which distributively stores energy representative of a signal sampled thereby. Such a device has particular utility in a distance-measuring equipment and, hence, will be described in that environment.

One type of signal-sampling device heretofore proposed features a series of cascade-coupled electron tubes involving fairly complex circuit connections which may sometimes be objectionable. Another signal-sampling device utilizing a vapor-electric or gas-discharge tube is described in Patent No. 2,553,263, granted to Arthur V. Loughren on May 15, 1951. While such a vapor-electric tube has several advantages, it may be desirable for some applications to utilize a high-vacuum tube to provide greater operating stability. Another signal-sampling system has been proposed utilizing a time-delay device to control a signal-sampling operation of a series of diodes coupled thereto. This system is somewhat complex in circuitry and is undesirably bulky.

It is an object of the present invention, therefore, to provide a new and improved electron-discharge signal-sampling device which avoids one or more of the aforementioned limitations of devices heretofore proposed.

It is another object of the invention to provide a new and improved electron-discharge signal-sampling device of compact construction.

It is another object of the invention to provide a new and improved electron-discharge signal-sampling energy-storage device for distributively storing energy representative of a signal sampled thereby.

In accordance with a particular form of the invention, an electron-discharge signal-sampling device comprises first terminals for supplying a signal to be sampled and second terminals for supplying a control pulse. The device includes a space-current electrode coupled to the first terminals and a time-delay signal-translating device coupled to the second terminals and having at least one pick-off electrode for developing a sampling pulse and comprising a space-current electrode. The device further includes a primary space-current electrode common to the other space-current electrodes and cooperating therewith to cause space-current flow representative of a sample of the aforementioned signal.

For a better understanding of the present in-

2

vention, together with other and further objects thereof, reference is had to the following description taken in connection with the accompanying drawings, and its scope will be pointed out in the appended claims.

In the accompanying drawings Fig. 1 is a circuit diagram, partly schematic, of a distance-measuring equipment including an electron-discharge signal-sampling device constructed in accordance with the invention; Fig. 1a is a diagrammatic representation of the electron-discharge signal-sampling device of the Fig. 1 equipment; Fig. 2 is a graph representing the output signals of various units of the Fig. 1 equipment; Fig. 3 is a graph representing space-potential distribution characteristics of elements of that equipment for use in explaining the operation thereof; while Fig. 4 diagrammatically represents an electron-discharge signal-sampling energy-storage device, constructed in accordance with another form of the invention.

General description of Fig. 1 distance-measuring equipment

Referring now more particularly to Fig. 1 of the drawings, the distance-measuring equipment there represented may be installed on an aircraft. The transmitter portion of the equipment includes, coupled in cascade, a master oscillator 10, a modulator 11, and a wave-signal transmitter 12 designed to transmit challenging wave signals of pulse wave form which may comprise single pulses or groups of pulses of relatively short pulse duration and having a repetition rate of, for example, 10 cycles per second. An antenna system 13, 14 is connected to the output circuit of the transmitter 12 and also to the receiver portion of the equipment which comprises a duplexer and wave-signal receiver 15. The receiver of the unit 15 may be of any suitable type, such as a superregenerative or a superheterodyne receiver for receiving and selecting target signals effectively generated at remote points by, for example, ground beacons and intercepted by the antenna system 13, 14. The duplexer of the unit 15 is any well-known protective device for protecting the receiver during operating intervals in which the transmitter 12 sends out a challenging signal, such as one of the devices described in Chapter XI of the text "Principles of Radar," second edition, by the Massachusetts Institute of Technology Radar School Staff, McGraw-Hill, 1946.

The output circuits of the modulator 11 and the receiver of the unit 15 are connected to

input circuits of an electron-discharge signal-sampling device 16 through coupling-condenser and grid-leak-resistor circuits 17, 18 and 19, 20, respectively, having suitable sources of bias potential such as batteries 50 and 51, respectively, connected thereto. The device 16 is constructed in accordance with the invention and will be described hereinafter. The output circuits of the device 16 are individually connected to condensers 21a-21h, inclusive, which have a common terminal connected to a suitable source of positive potential +B.

The noncommon terminals of condensers 21a-21h, inclusive, are connected to terminals 22a-22h, inclusive, respectively, of a rotatable switch 22 having a rotor 23. A direct-current voltmeter 24 is connected between the rotor 23 and the negative terminal -B of the source for measuring the potentials developed at the various terminals. The noncommon terminals of condensers 21a-21h, inclusive, are also individually connected to a series of contacts of a switch unit 25 of conventional construction for making and breaking connections between the noncommon terminals of the condensers 21a-21h, inclusive, and the source +B. A motor 26 is connected to drive the switch unit 25, as indicated by the broken line 27. Units 10-12, inclusive, and 15, the antenna system 13, 14, the motor 26 and the switch unit 25 may all be of conventional construction and operation so that a detailed explanation of the operation thereof is deemed unnecessary.

General operation of Fig. 1 distance-measuring equipment

Considering briefly, however, the operation of the Fig. 1 distance-measuring equipment as a whole, the master oscillator 10 periodically applies to the modulator 11 trigger pulses having a repetition frequency determined by the oscillator frequency. The trigger pulses from the oscillator 10 periodically fire the modulator 11 which, in turn, pulse-modulates the output signal of the transmitter 12 and causes the transmitter to apply to the antenna system 13, 14 periodic bursts of high-frequency wave-signal energy. During the operation of the transmitter 12, the duplexer of the unit 15 protects the receiver thereof from being overloaded by the transmitted pulses. During the intervals between transmitted pulses, the receiver of the unit 15 responds to any target signals intercepted by the antenna system 13, 14, detects the modulation components of these signals and applies the detected signals to the electron-discharge signal-sampling device 16.

The curves of Fig. 2 represent the operation of the distance-measuring equipment during two operating periods thereof. Curve A represents the amplitude-time characteristic of the output signal of the modulator 11 applied thereby to the signal-sampling device 16 and curve B represents the amplitude-time characteristic of the output signal of the receiver of the unit 15, also applied to an input circuit of the device 16.

In response to the signals just mentioned, the device 16 develops a charge on one of the condensers 21a-21h, inclusive, selected by the device in accordance with the time interval t_0-t_1 between each modulator pulse of curve A and the corresponding target pulse of curve B, as will be more fully explained hereinafter. The condenser selection made by the device 16 then represents the distance between the transmitter 12 and the target. As the switch arm 23 of the switch 22 is

adjusted to the various terminals 22a-22h, inclusive, its position in conjunction with the reading of the meter 24 indicates which condenser is charged by the device 16. Accordingly, the positions of adjustment of the switch arm 23 may be calibrated in terms of distance, thereby to indicate the distance between the transmitter 12 and the target.

Description of Fig. 1 signal-sampling device

Referring now more particularly to the electron-discharge signal-sampling device 16 of Fig. 1, that device comprises first terminals for supplying a signal to be sampled, specifically, a pair of input terminals 28, 28 coupled to the receiver of the unit 15. The device also includes second terminals for supplying a control pulse comprising a pair of input terminals 29, 29 coupled to the modulator 11.

The device 16 further includes a first space-current electrode coupled to the terminals 28, 28. This electrode preferably comprises an elongated first control electrode 30 of grid-like structure. The device also preferably includes a second accelerating electrode 31 of similar structure connected to a bias potential-supply circuit comprising a voltage-dropping resistor 52 and the source +B.

There is also provided at least one time-delay signal-translating device coupled to the terminals 29, 29 and having at least one pick-off electrode for developing a sampling pulse. The time-delay device preferably has a plurality of spaced pick-off electrodes for developing successive sampling pulses and comprising space-current electrodes, in particular, effectively electrically isolated space-current control electrodes. More particularly, the signal-sampling device 16 includes one or more, for example, two adjacent elongated time-delay signal-translating devices 33 and 33' of similar construction positioned parallel to each other with an intervening space therebetween for the passage of space-current flow as represented in Fig. 1a which is a diagrammatic end view of the Fig. 1 electron-discharge device 16. Corresponding elements represented in Figs. 1 and 1a have the same reference numerals.

Fragmentary portions of the devices 33 and 33' are shown in Fig. 1 of the drawing, partially in cross section. The device 33 extends out of view along the device 33' and preferably comprises a tube 34 of rectangular cross section comprising electrostrictive material, such as barium titanate bonded with a ceramic binder. A tube 35 of suitable conductive material is positioned within the electrostrictive tube 34. The inner tube 35 may comprise, for example, a suitable metallic coating on the inner surface of the tube 34. A plurality of relatively short, metallic tubes 36e-36h, inclusive, and several others not shown are positioned along the outer surface of electrostrictive tube 34 at suitable intervals to form together with corresponding portions of the coating 35 several pairs of spaced pick-off electrodes. Any suitable number of such pick-off electrodes may be utilized. A block of damping material 37, such as Wood's metal comprising 8 parts bismuth, 4 lead, 2 tin and 1 or 2 parts cadmium, preferably is attached to each end of the electrostrictive tube 34 for terminating the device 33 with its characteristic impedance to minimize end energy reflections.

The fragmentary portion of the time-delay signal-translating device 33' shown in the drawing comprises elements similar to those just de-

scribed in connection with device 33, corresponding elements being designated by similar reference numerals primed, including several pick-off electrodes spaced along the portion of the device 33' not shown in a manner similar to the electrodes 36e-36h, inclusive, of the device 33. The device 33' has an input electrode 36' which together with the coating 35' is coupled to the output circuit of the modulator 11 for applying to the device 33' an input signal to be sampled. The output circuit of the modulator 11 is also coupled in a similar manner to the device 33, as indicated by the conductors 38, 38, the devices 33 and 33' being connected in parallel.

The devices 33 and 33' preferably are permanently electrically polarized by the temporary application of a high potential across the inner and outer pick-off electrodes thereof to improve the response of the devices to applied signals. Also, for a reason which will become apparent hereinafter, adjacent pick-off electrodes on individual ones of the devices 33 and 33' preferably have overlapping response characteristics to stress pulses propagated along the individual devices.

The electron-discharge signal-sampling device 16 also includes a primary space-current electrode common to the other space-current electrodes and cooperating therewith to cause space-current flow representative of the successive samples of the signal to be sampled. Specifically, this primary space-current electrode comprises an elongated cathode 39 having a cathode load resistor 40. By "primary space-current electrode" is meant an electron-emitting electrode or an electron-collecting electrode.

The device 16 also includes a plurality of anodes 41a-41h, inclusive, spaced therealong and corresponding to the pick-off electrodes 36a'-36h', inclusive, and 36a-36h, inclusive, respectively. The anodes 41a-41h, inclusive, are connected to the noncommon terminals of condensers 21a-21h, inclusive, respectively. The several electrodes and the time-delay signal-translating devices 33 and 33' preferably are enclosed in a single evacuated envelope 42.

Potential-supply circuit means for maintaining normally nonconductive the individual portions of the electron-discharge signal-sampling device 16 corresponding to the spaced pick-off electrodes 36a'-36h', inclusive, and 36a-36h, inclusive, comprise the potential-supply terminals connected to the various electrodes of the device 16, for example, the terminals 28, 28 and 29, 29.

Operation of Fig. 1 signal-sampling device

The bias potentials applied to the various electrodes of the signal-sampling device 16 and, in particular, the potentials applied thereto at the terminals 28, 28 and 29, 29 are effective to maintain the device 16 normally non-conductive along the length thereof. The modulator 11 periodically applies the repetitive pulses represented by curve A to the input electrodes 35', 36' of the time-delay device 33' and to the corresponding input electrodes of the time-delay device 33. These repetitive pulses are converted to corresponding mechanical expansions and constrictions of the electrostrictive elements 34 and 34' and are propagated as pulses of mechanical stress along the time-delay devices 33 and 33', respectively, at a rate determined by the time-delay characteristics thereof. As the mechanical stress pulses travel by each of the pick-off electrodes 36a'-36h', inclusive, and 36a-36h, inclusive, of the

devices 33 and 33', respectively, electrical positive-potential sampling pulses are successively developed at those pick-off electrodes. The sampling pulse developed at each pick-off electrode, however, is ineffective to render the corresponding portion of the device 16 conductive in the absence of a simultaneous increase of the potential at the control electrode 30.

Curve B of Fig. 2 represents the output signal of the duplexer and wave-signal receiver 15 which, as a signal to be sampled, is applied to the control electrode 30 of the device 16. The signal represented by curve B periodically raises the potential of the control electrode 30 uniformly along the length thereof. Curve C of Fig. 3 represents the space-potential distribution characteristic of the control electrode 30 at the time t_1 when the first pulse of curve B is applied thereto. At this time in response to the mechanical stress pulses propagated along the time-delay devices 33' and 33, there also occur increases of the potentials at corresponding selected pick-off electrodes of the devices 33' and 33, for example, at the electrodes 36c' and 36c, respectively. The corresponding pick-off electrodes are selected in accordance with the time-delay characteristics of the time-delay devices 33' and 33. Curve D of Fig. 3 represents the pulse-shaped space-potential distribution characteristic of each of the time-delay devices 33' and 33 at the time t_1 .

The electrical pulse represented by curve D and developed at the pick-off electrodes 36c' and 36c and the positive potential developed at the corresponding region of the control electrode 30 at the time t_1 are effective to render conductive the portion of the device 16 corresponding thereto, while the remainder of the device 16 remains nonconductive. Of course, the cathode 39 cooperates with the other space-current electrodes in rendering conductive the selected portion of the device 16 in response to the sampling pulses developed at the selected pick-off electrodes at the time t_1 to cause space-current flow representative of a sample of the output signal of the receiver of the unit 15. Further, the magnitude of the space-current flow at the time t_1 is representative of the magnitude of the signal which is sampled at that time and, similarly, the magnitude of space-current flow during successive intervals is representative of successive samples of the signal. Accordingly, at the time t_1 a negative incremental charge having a magnitude representative of a signal sample is developed on the condenser 21c corresponding to the electrodes 36c' and 36c. During each cycle of the operation of the distance-measuring equipment an additional incremental charge is acquired by the condenser 21c until the condenser is charged to such a value that the potential of the anode 41c drops to a value too low to cause that portion of the device 16 to become conductive.

Since each negative incremental charge acquired by any given condenser has a magnitude representative of a corresponding signal sample, in the absence of stray signals no charges are acquired by the condensers 21a, 21b, and 21d-21h, inclusive, during the intervals between the pulses of curve B of Fig. 2 because the signal to be sampled may be considered to have zero magnitude during those intervals. Further, because the condenser 21c periodically acquires at the time t_1 and corresponding times during successive cycles an incremental charge having a magnitude representative of a signal sample, the condenser 21c charges more rapidly than any other condenser.

sers which may be charged in response to stray signals occurring at random times.

The fact that the condenser 21c has acquired a negative charge may be indicated by rotating the switch arm 23 to the terminal 22c connected thereto. Since the positions of the adjustment of the switch arm may be calibrated in terms of distance, the distance between the transmitter and the target causing a response at the time t_1 is thereby indicated. In the event that a target pulse should appear at a different time after the transmission of each transmitted pulse, a different portion of the device 16 will be rendered conductive and a different condenser will be charged, providing a different indication of distance on the switch 22.

As previously mentioned, stray signals may render conductive various portions of the device 16 at random times and cause the corresponding condensers 21a-21h, inclusive, slowly to acquire random charges in addition to the charging of the condenser 21c which occurs in response to a target signal. Accordingly, the motor 26 and switch unit 25 are utilized periodically to discharge the condensers at a rate of, for example, once every four seconds. For this purpose, the switch unit 25 periodically connects the non-common terminals of the condensers 21a-21h, inclusive, to the source +B connected to the switch unit in a conventional manner.

Under certain operating conditions a pulse representative of a target may be derived by the receiver of the unit 15 at a time when the stress pulse traveling along either time-delay device is intermediate two adjacent pick-off electrodes. Then, because of the overlapping response characteristics of the adjacent pick-off electrodes, two adjacent portions of the device 16 are rendered conductive and two corresponding condensers are charged. The fact that two condensers are charged indicates that the target position is intermediate the distances corresponding to the condensers and the relative instantaneous magnitudes of the charges on the condensers during the charging times thereof are representative of the relation of the target position to the distances corresponding to the charged condensers.

Description of Fig. 4 signal-sampling energy-storage device

Referring now more particularly to Fig. 4, there is represented an electron-discharge signal-sampling energy-storage device for distributively storing energy representative of a signal sampled thereby. This device is generally similar to the Fig. 1 signal-sampling device 16, corresponding elements being designated by similar reference numerals primed and double-primed. The device 16', however, includes a single time-delay signal-translating device 33'' which has a plurality of spaced pick-off electrodes 36a''-36h'', inclusive, for developing successive sampling pulses and comprising effectively electrically isolated anodes rather than control electrodes. As described in connection with the device 33 of Fig. 1, each pair of pick-off electrodes comprising a portion of the inner coating 35'' and one of the electrodes 36a''-36h'', inclusive, is separated by dielectric material comprising an electrostrictive element 34''. Accordingly, a plurality of energy-storage means comprises the pairs of pick-off electrodes which are effective as condensers to perform the functions of the condensers 21a-21h, inclusive, of Fig. 1. The pick-off electrodes

36a''-36h'', inclusive, therefore, are directly connected to the terminals 22a'-22h', inclusive, respectively, of a switch 22'.

Operation of Fig. 4 signal-sampling energy-storage device

The operation of the Fig. 4 device is analogous to that of the Fig. 1 device. While the device 16' is normally nonconductive along the length thereof, the appearance of a target pulse at a given time after each corresponding transmitted pulse causes an increase of the potential at the control electrode 30'. At this time the potential at a selected one of the pick-off anode electrodes 36a''-36h'', inclusive, rises sufficiently to render conductive the corresponding portion of the device 16'. The magnitude of the space-current flow at the time t_1 is representative of the magnitude of the signal to be sampled at that time because of the control over space-current flow exerted by the control electrode 30' in cooperation with the selected pick-off electrode as an anode. Also, by successively conditioning the remaining individual portions of the device 16' for conduction, the pick-off electrodes cooperate with the first space-current electrode 30' to cause space-current flow representative of successive samples of the signal to be sampled. The pick-off electrodes in response to the space-current flow also are effective as condensers for distributively storing energy representative of the samples. The charged pairs of pick-off electrodes may be periodically discharged in a manner similar to that explained in connection with the discharging of the condensers 21a-21h, inclusive, of Fig. 1.

From the foregoing description of the invention, it will be apparent that an electron-discharge signal-sampling device constructed in accordance with the invention has the advantage of compact construction and further may be so constructed as to function as an electron-discharge signal-sampling energy-storage device for distributively storing energy representative of a signal sampled thereby.

While there have been described what are at present considered to be the preferred embodiments of this invention, it will be obvious to those skilled in the art that various changes and modifications may be made therein without departing from the invention, and it is, therefore, aimed to cover all such changes and modifications as fall within the true spirit and scope of the invention.

What is claimed is:

- An electron-discharge signal-sampling device comprising: first terminals for supplying a signal to be sampled; second terminals for supplying a control pulse; an elongated first control electrode coupled to said first terminals; an elongated electrostrictive time-delay signal-translating device coupled to said second terminals and having a plurality of spaced pick-off electrodes for developing successive sampling pulses and comprising effectively electrically isolated space-current control electrodes; and an elongated cathode common to said first control electrode and said isolated control electrodes and cooperating therewith to cause space-current flow representative of successive samples of said signal.
- An electron-discharge signal-sampling device comprising: first terminals for supplying a signal to be sampled; second terminals for supplying a control pulse; a space-current electrode coupled to said first terminals; a time-delay signal-translating device coupled to said second

terminals and having at least one pick-off electrode for developing a sampling pulse and comprising a space-current electrode; and a primary space-current electrode common to the other space-current electrodes and cooperating therewith to cause space-current flow representative of a sample of said signal.

3. An electron-discharge signal-sampling device comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising space-current electrodes; and a primary space-current electrode common to the other space-current electrodes and cooperating therewith to cause space-current flow representative of successive samples of said signal.

4. An electron-discharge signal-sampling device comprising: first terminals for supplying a signal to be sampled; second terminals for supplying a control pulse; an elongated space-current electrode coupled to said first terminals; an elongated electrostrictive time-delay signal-translating device coupled to said second terminals and having a plurality of spaced pick-off electrodes for developing successive sampling pulses and comprising space-current electrodes; and an elongated primary space-current electrode common to the other space-current electrodes and cooperating therewith to cause space-current flow representative of successive samples of said signal.

5. An electron-discharge signal-sampling device comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising effectively electrically isolated space-current control electrodes; and a primary space-current electrode common to the other space-current electrodes and cooperating therewith to cause space-current flow representative of successive samples of said signal.

6. An electron-discharge signal-sampling device comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising effectively electrically isolated anodes; and a primary space-current electrode common to the other space-current electrodes and cooperating therewith to cause space-current flow representative of successive samples of said signal.

7. An electron-discharge signal-sampling device comprising: first terminals for supplying a signal to be sampled; second terminals for supplying a control pulse; a space-current electrode coupled to said first terminals; a time-delay signal-translating device comprising an elongated tube of electrostrictive material and an elongated inner tube of conductive material concentric therewith and coupled to one of said second terminals, said time-delay device having an outer tubular input electrode positioned along said electrostrictive tube and coupled to another of said second terminals and having outer tubular pick-

off electrodes spaced along said electrostrictive tube and cooperating with said conductive tube for developing successive sampling pulses and comprising space-current electrodes; and a primary space-current electrode common to the other space-current electrodes and cooperating therewith to cause space-current flow representative of successive samples of said signal.

8. An electron-discharge signal-sampling device comprising: first terminals for supplying a signal to be sampled; second terminals for supplying a control pulse; a space-current electrode coupled to said first terminals; a plurality of similar time-delay signal-translating devices connected in parallel to said second terminals and having a plurality of spaced pick-off electrodes for developing successive sampling pulses and comprising space-current electrodes; and a primary space-current electrode common to the other space-current electrodes and cooperating therewith to cause space-current flow representative of successive samples of said signal.

9. An electron-discharge signal-sampling device comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising space-current electrodes; and a cathode common to said space-current electrodes and cooperating therewith to cause space-current flow representative of successive samples of said signal.

10. An electron-discharge signal-sampling device comprising: first terminals for supplying a signal to be sampled; second terminals for supplying a control pulse; a cathode; a time-delay signal-translating device coupled to said second terminals and having a plurality of spaced pick-off electrodes for developing successive sampling pulses and comprising anodes; a space-current control electrode common to said anodes and coupled to said first terminals and positioned intermediate said cathode and said anodes; said cathode being common to said anodes and said control electrode and cooperating therewith to cause space-current flow representative of successive samples of said signal.

11. An electron-discharge signal-sampling device comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising space-current electrodes; potential-supply circuit means including said terminals for maintaining normally nonconductive individual portions of the electron-discharge device corresponding to said spaced pick-off electrodes; and a primary space-current electrode common to the other space-current electrodes and cooperating therewith for rendering conductive said individual portions in response to said sampling pulses and said signal and thus to cause space-current flow representative of successive samples of said signal.

12. An electron-discharge signal-sampling energy-storage device for distributively storing energy representative of a signal sampled thereby comprising: first terminals for supplying a

signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising space-current electrodes; a primary space-current electrode common to the other space-current electrodes and cooperating therewith to cause space-current flow representative of successive samples of said signal; and a plurality of energy-storage means individually including said pick-off electrodes for distributively storing energy representative of said samples.

13. An electron-discharge signal-sampling energy-storage device for distributively storing energy representative of a signal sampled thereby comprising: first terminals for supplying a signal to be sampled; second terminals for supplying a control pulse; a space-current electrode coupled to said first terminals; a time-delay signal-translating device coupled to said second terminals and having a plurality of spaced pick-off electrodes for developing successive sampling pulses and comprising space-current electrodes; a primary space-current electrode common to the other space-current electrodes and cooperating therewith to cause space-current flow repre-

sentative of successive samples of said signal; and a plurality of condensers individually including said pick-off electrodes as one plate of each thereof for distributively storing energy representative of said samples.

14. An electron-discharge signal-sampling energy-storage system for distributively storing energy representative of a signal sampled thereby comprising: an electron-discharge signal-sampling device including first terminals for supplying a signal to be sampled, second terminals for supplying a control pulse, a space-current control electrode coupled to said first terminals, a time-delay signal-translating device coupled to said second terminals and having a plurality of spaced pick-off electrodes for developing successive sampling pulses and comprising space-current control electrodes, a cathode common to the other space-current electrodes and cooperating therewith to cause space-current flow representative of successive samples of said signal, a plurality of spaced anodes individually corresponding to said spaced pick-off electrodes; and a plurality of condensers individually coupled to said anodes for distributively storing energy representative of said samples.
